UNITED STATES PATENT OFFICE.

CHARLES H. BEELER, JR., OF PHILADELPHIA, PENNSYLVANIA, ASSIGNOR TO
MACKELLAR, SMITHS & JORDAN, OF SAME PLACE.

DESIGN FOR A FONT OF PRINTING-TYPE.

SPECIFICATION forming part of Design No. 14,564, dated January 29, 1884.

Application filed November 24, 1883. Term of patent 7 years.

To all whom it may concern:

Be it known that I, CHARLES H. BEELER, Jr., (assignor to MACKELLAR, SMITHS & JORDAN,) of the city and county of Philadelphia, 5 Pennsylvania, have invented and produced a new and original Design for a Font of Printing-Type, of which the following is a specification.

The nature of my design is clearly shown in the accompanying typographic impression, to 10 which reference is made; and it consists of a heavy unshaded inclined letter, the lower terminations of the up and down portions of which are curved to the right, as clearly shown 15 in the E, F, H, K, L, P, R, T, V, W, X, Y, and Z. The cross-lines of the A and H con-

sist of the heavy and light inclined lines, as shown. The C, E, F, and G have the ball termination, as shown, upon the right hand.

The character of the design is preserved in the lower case and in the numerals, as clearly 20 shown.

Having now described my invention, I claim as new—

The design for a font of printing-type, substantially as shown and described.

C. H. BEELER, JR.

In presence of—

C. F. HUCH,
HERMAN METIUS.
